TOOL CONSTRUCTION

Major R. Ford, Mill Port, N. Y.

Application August 18, 1936, Serial No. 96,561

1 Claim. (Cl. 306—33)

The invention herein disclosed relates to tools and in particular to that type of tool, such as the pickax and mattock, in which the handle is provided with an outwardly flaring, tool-engaging, end section and the tool is provided with a complementary socket to receive the outwardly flaring end section of the handle.

In tools of this type, the tool is held in place on the handle by being wedged on the flaring end section of the handle and the tool frequently becomes loose on the handle when the tool is in use. When this occurs, the tool slides along the handle and against the hands or body of the one using the tool. This condition is not only dangerous to the one using the tool, but when once the tool becomes loose on the handle it is a difficult and in many cases practically impossible to again wedge the tool on the handle such that it will not again become loose.

It is an object of this invention to provide a tool-securing element which when utilized in conjunction with tools of the type mentioned, firmly secures the tool in place on the flared end of the handle such that the tool cannot be loosened and in any event cannot slide down along the handle.

When once wedged on the flared end section of the handle, the tool can become loose only by being moved along the flare and thus loosening the tight frictional engagement between the side of the flared end-section of the handle and the walls of the socket formed in the tool. Such movement of the tool is restrained in accordance with this invention by providing a tool-securing element that includes a section which engages the constricted edge of the socket in the tool, a section that extends along the flared tool-engaging end-section of the handle and between the handle and the wall of the socket of the tool, and a section which engages the end of the handle. This tool-retaining element serves to hold the tool in the position on the handle on which it is wedged. And since the tool is held in the position in which it is wedged it cannot become loosened.

A tool constructed in this manner is illustrated in the accompanying drawing in which:

Fig. 1 is a transverse section of the tool;

Fig. 2 is an end view of the same; and

Fig. 3 is an end view of a modified form of tool.

In the drawing, the tool 1 is illustrated as mounted upon a handle 2. The handle 2 has a flared, tool-engaging, end-section 3 and the tool 1 has a complementary socket 4 in which the flared, tool-engaging, end-section 3 of the handle 2 is received. In mounting the tool on the

handle, the grip end of the handle is inserted through the socket of the tool and the tool is moved along the handle until the flared, tool-engaging, end-section 3 of the handle is received within the socket 4. The section 3 of the handle is then wedged in the socket.

In mounting the handle on the tool, there is inserted a tool-retaining element 5 which consists of a piece of steel stock of approximately one-eighth of an inch in thickness. One end of this piece of stock is bent to form a flange 5a which engages the edge of the constricted end of the socket. A central section 5b extends along the wall of the socket and between the wall of the socket and the surface of the flared end section 3 of the handle. When the handle is inserted, the tool-retaining element extends beyond the edge of the socket as indicated at 5c. After the tool has been firmly wedged upon the flared, tool-engaging end 3 of the handle, the section 5c is bent over to form a flange 5d that engages the end of the handle 2.

The tool shown in Figs. 1 and 2 has a socket that is substantially square in cross-section. In such a tool, the tool-retaining element 5 extends along one wall of the socket and may be of the same width as the wall of the socket. The tool-retaining element is of course tapered in accordance with the walls of the socket. When the section 5c has been bent over to form the flange 5d, it will be seen that the tool-retaining element 5 firmly secures the tool in the position on the flared end of the handle in which it was wedged on to the handle. The tool cannot, therefore, move along the handle and thus become loosened and slide along the handle.

In Fig. 3 there is illustrated a tool 1' in which the socket is of oval shape. In such a tool, the tool-retaining element 5' may be narrower than the one used with a square socket. The tool-retaining element may be shaped in accordance with the curvature of the handle, but is preferably placed at the flat section of the oval where it presents least interference with forming a tight wedge between the walls of the socket of the tool and the flared end of the handle. Its construction and operation in a tool having an oval shaped socket or even a round socket is the same as with a tool having a square socket.

From the above description of the embodiments of the invention illustrated in the drawing, it will be seen that by the invention there is provided a tool-retaining element by which, and tool construction in which, the tool is securely held in the position in which it is wedged on

the handle and it cannot become loosened or slide along the handle.

It will be obvious that various modifications may be made by those skilled in the art in the details of the construction illustrated in the drawing and described in detail above within the principle and scope of my invention as expressed in the appended claim.

I claim:

- 10 In a tool having a handle with an outwardly flaring, tool-engaging end section and a tool having a complementary socket to receive the flared end of the handle, a tool-retaining element for retaining the tool in position on the handle com-

prising a single flat piece of sheet metal of relatively narrow and substantially uniform width consisting of a flanged section extending outwardly over the edge of the socket in the tool at the restricted end of the socket and engaging the inner face of the tool, a longitudinal section extending along the wall of the socket and between the wall of the socket and the flared end section of the handle, and a flanged end section extending inwardly over and engaging the outer 10 end of the handle and terminating thereon, whereby the direct wedging contact between the socket and flared end of the tool handle is substantially continuous.
